UNITED STATES PATENT OFFICE.

GUSTAV J. GRUENDLER, OF CLAYTON, MISSOURI.

REFRIGERATOR.

Application filed May 22, 1926. Serial No. 110,929.

My invention relates to refrigerators and more particularly to refrigerators of the show-case type which have in the front and top walls of the storage chamber thereof 5 transparent panels through which the goods displayed in the storage chamber may be seen.

Heretofore in refrigerators of this type the refrigerant containers have been positioned at one or both ends of the storage chamber with the result that the storage chamber extended only from one half to two thirds of the length of the refrigerator and that from one third to one half of the 15 length of the refrigerator was used for chambers in which were mounted the refrigerant containers. These chambers occupied by the refrigerator containers although, of course, cooled to a very low temperature could not be used for storing provisions.

The objects of this invention are to provide a refrigerator wherein the refrigerant containers for cooling the storage chamber 25 thereof are so positioned and arranged that the storage chamber of the refrigerator will extend the whole length of the refrigerator and to provide in a refrigerator one or more refrigerant containers which may be quickly and easily charged with a refrigerant and which may be quickly and easily emptied 30 and then moved from the refrigerator to be cleaned.

A practical embodiment of my invention 35 is fully shown in the accompanying drawings wherein similar characters are used to designate similar parts; Figs. 1, 3, 4 and 5 are top, front, back and end views, respectively, of the refrigerator embodying my 40 invention; Fig. 2 is a section along the lines 2—2 in Fig. 3; Fig. 6 is a section taken generally along the lines 6—6 in Fig. 4; and Fig. 7 shows a detail of construction, as will be more fully hereinafter set forth.

In this embodiment of my invention the 45 refrigerator has an elongated storage chamber 1 which has in its front wall transparent panels 2 and in its top wall transparent panels 3. The rear wall of the storage 50 chamber for a portion of its length is inclined, as shown in Figs. 5 and 6, and has mounted therein a plurality of doors 4 which may contain transparent panels and which are positioned and arranged so that 55 articles may be put into or taken from the storage chamber 1 through the door open-

ings. The storage chamber 1 also has a bottom wall 5 which is, in this form of my invention, positioned above the bottom of the refrigerator, since, as shown, the storage 60 chamber is formed only in the upper part of the refrigerator. All of the walls of the storage chamber are, of course, properly insulated. A shelf 6 for provisions and, preferably, made in a number of sections to 65 facilitate its removal from the storage chamber is supported therein by the S-shaped hangers 7 and the angle brackets 8 mounted on the walls of the refrigerator at intervals along the length of the shelf 6, as clearly 70 shown in Figs. 2 and 6.

In this embodiment the storage chamber 1 has therein two containers adapted to be charged with ice or some other refrigerant, preferably, positioned along and spaced 75 from the bottom wall 5 of the storage chamber and, as shown in Fig. 2, substantially co-extensive therewith. Each of these containers comprise in this form of my invention a rectangular header 9 open at the top 80 and a plurality of tubes 10 extending therefrom. I prefer that the containers be positioned in the storage chamber with the headers 9 at the rear of the refrigerator and the tubes 10 extending forwardly towards 85 the front thereof so that the front of the storage chamber will be open and an unobstructed view of the provisions stored therein may be had. Also, this positioning of containers allows them to be more readily 90 charged with ice or other refrigerant, in the manner more fully hereinafter described. The containers are supported by the blocks 11 arranged under the header 9 and the strips 12 arranged under the tubes 95 10. The rear wall of the refrigerator has in that part thereof which is substantially horizontal one or more substantially horizontally disposed openings 13, preferably, as long as one of the containers and each positioned above one of the headers 9 and normally closed by a closure 13a. Also, the rear wall has in that portion thereof which is substantially vertical one or more substantially vertically disposed openings 14 each 100 positioned behind and as long as one of the containers and otherwise adapted and arranged so that one of the containers may be moved therethrough, as hereinafter set forth. Each of the openings 14 is normally 105 closed by a closure 14a.

Each of the containers has an overflow

pipe 16 which has perforations 17 near its upper end and which is threaded at its lower end into the boss 18 carried by the bottom of the header 9. The bottom of the header 9 has therein an opening which substantially registers with the passage through the pipe and, therefore, that portion of the bottom of the header adjacent the opening forms a shoulder 19 extending inwardly at the lower edge of the boss 18 to engage the lower end of the wall of the pipe 16 when it is turned into the boss.

A sump 20 is provided in substantially the longitudinal center of the bottom wall 5 of the storage chamber and, preferably, near the rear thereof and is of a length to extend under the discharge opening of the overflow pipe 16 in both of the refrigerant containers, as shown in Fig. 2 and in detail in Fig. 7. The waste pipe 22 has the upper end thereof projecting upwardly a short distance above the bottom of the sump 20 and a perforated cap 21 is provided over the projecting end of the waste pipe, all as shown. The waste pipe 22 may lead by complementary connections to a sewer or other place of discharge, not shown.

A scale stand 23 may be provided at the back of the refrigerator, as shown in the figures. Also a shelf 25 for storing imperishable goods may be arranged in the lower part of the refrigerator.

The operation of this embodiment of my new and improved refrigerator is as follows: When the containers are in position in the storage chamber 1 the closures 13^a are removed from the openings 13 and a refrigerant such as cracked ice and salt is poured into each of the containers through the open tops of the headers 9 and is forced into the tubes 10. I prefer that the openings of the tubes 10 into the headers 9 be substantially the same area as the cross-section of the tubes themselves and if formed in this way I have found that the cracked ice may be quickly and easily tamped into the tubes to fill them throughout their entire length. A shield 15 may be provided to prevent any of the cracked ice from falling downwardly at the rear of the headers 9 into the space between the headers and the adjacent wall. After the containers have been charged with a refrigerant the closures 13^a are replaced.

The brine resulting from the melting of the ice will be collected in the containers until the water has filled the tubes 10 and has reached the perforations 17 at the upper end of the overflow pipes 16. In some instances the containers may be filled with brine and then the brine may be cooled by placing the ice in it or by any other means. The perforations 17 may be placed at any point in the overflow pipes 16 to create and maintain any desired predetermined level

of brine in the containers and in turn to collect a predetermined amount of brine therein. The surplus brine resulting from the further melting of the ice in each container will pass through the perforations downwardly through the overflow pipe 16 into the sump 20 from where it will drain through the waste pipe 22, as explained above. When the ice is all melted and it is desired to move the containers from the refrigerator for cleaning the closures 13^a are removed from the horizontally disposed openings 13, and the closures 14^a are removed from the vertically disposed openings 14. The overflow pipes 16 are unscrewed from the bosses 18 thereby allowing the collected brine in the containers to drain therefrom. The containers will then be light and easily handled and may be easily removed through the substantially vertically disposed openings 14. After the containers have been cleaned they are replaced through the openings 14, the overflow pipes 16 are screwed into the bosses 18, the containers are then charged, as described above, and the closures 13^a and 14^a are replaced.

Since, as set forth, the containers are each spaced from the bottom wall 5 of the storage chamber 1 by means of the blocks 11 and the strips 12, air may circulate all around the headers 9 and the tubes 10 and may contact with all portions of the cold exposed area of the containers and a low temperature will be created in the entire storage chamber. I prefer that the containers are substantially co-extensive with the bottom wall 5 of the storage chamber, as described, so that the entire storage chamber may be maintained at approximately the same temperature and that one part thereof will not be warmer or colder than another part.

While, as stated above, the refrigerator described herein embodies one form of my invention in which ice or a similar refrigerant is used it may be readily understood that other embodiments of my invention may be made to use other refrigerants and the shape, size and arrangement of the various parts may be varied within wide limits without deviating from the spirit of the claims set forth below.

What I claim as new and desire to secure by Letters Patent, is:—

1. A show-case refrigerator having an elongated storage chamber therein, a container for ice positioned along the bottom wall of said storage chamber, the walls of said storage chamber having therein a substantially horizontally disposed opening through which said container may be charged with ice and a substantially vertically disposed opening through which said container may be moved from said refrigerator, and closures for said openings.

2. A show case refrigerator having a storage chamber therein, one or more containers for ice positioned along and spaced from the bottom wall of said storage chamber and substantially co-extensive therewith, each of said containers comprising a header and a plurality of tubes extending therefrom, and the walls of said storage chamber having an opening positioned above said header through which said containers may be charged with ice and an opening behind one of said containers through which said container may be moved from said refrigerator, and closures for said openings.
- 5 3. A show-case refrigerator having an elongated storage chamber therein, one or more containers for a refrigerant positioned along and spaced from a bottom wall of said storage chamber, each of said contain- ers comprising a header positioned at the rear of said storage chamber and a plurality of tubes extending forwardly therefrom, said refrigerator having in a substantially horizontally disposed wall thereof an opening through which one of said containers 20 may be charged with ice and having in a substantially vertical wall thereof an opening through which one of said containers may be moved from said refrigerator, closures for said openings, means for collecting 25 a predetermined amount of brine in said containers, and means for draining said collected brine from said refrigerator before 30 said containers are moved from said refrigerator.
- 10 15 35
- In witness whereof I have signed my name to this specification.
- GUSTAV J. GRUENDLER.
